UNITED STATES PATENT OFFICE.

WESLEY LINFORD SMITH, OF PITTSBURGH, PENNSYLVANIA.

ARTIFICIAL TOOTH.

1,238,210.

Specification of Letters Patent. Patented Aug. 28, 1917.

Application filed November 15, 1916. Serial No. 131,402.

To all whom it may concern:

Be it known that I, WESLEY LINFORD SMITH, a citizen of the United States, and resident of Pittsburgh, in the county of Allegheny and State of Pennsylvania, have invented a new and useful Improvement in Artificial Teeth; and I do hereby declare the following to be a full, clear, and exact description thereof.

10 My invention pertains to artificial teeth, and relates especially to the means for anchoring in place, in the body of the tooth, the securing pins which are ordinarily employed in connection with such teeth.

15 It is an object of the present invention to provide an anchoring means for the securing pin of an artificial tooth, which will retain such pin securely in position against all the ordinary strains to which the tooth

20 may be subjected. It is another object of the invention to provide an anchoring means for the securing pin, which will be easy to place in position, and the use of which will facilitate the manufacture of the 25 tooth and attached securing pin. Other and further objects of the invention will appear from the following specification, taken in connection with the appended claims.

By way of example, I have described in 30 the following specification and shown in the accompanying drawing, an artificial tooth constructed in accordance with my invention. I wish it understood, however, that changes may be made in the construction 35 described and shown, without exceeding the scope of the invention as defined in the appended claims.

In the drawing:

Figure 1 is a transverse section through 40 a mold which is employed in connection with the embodiment of my invention herein to be described;

Fig. 2 is an enlarged detail view showing the mold peg, and the conical anchor 45 carried thereby, the anchor being shown separate from the peg, for purposes of clearness;

Fig. 3 is a longitudinal section through 50 an artificial tooth, showing the same in condition which it assumes after the first fusing operation, and before the securing pin has been fixed therein; and

Fig. 4 is an enlarged longitudinal section taken through the completed artificial 55 tooth.

In carrying my invention into effect, I employ a mold consisting of an upper mold-member 10 and a lower mold-member 11, the two mold-members being constructed so as to form between them a chamber having 30 the shape of the tooth which is to be produced. In the lower member are mounted one or more pegs 12, having shanks 13 embedded in the body of the mold member. Usually two of these pegs 12 are provided, 35 disposed one beside the other. The end of each of the pegs 12 is made conical, as at 14, and is adapted to have mounted thereon a similarly shaped cap 15, formed of platinum or other refractory metal. 70

With the conical platinum cap 15, in place upon each of the pegs 12, the cavity of the mold member 11 is filled with the plastic composition of which the body of the tooth is composed. The cavity of the 75 mold member 10 is likewise packed with composition. The mold members are then superposed one upon the other, and are placed in a moderately heated press, wherein they are subjected to pressure. The effect of the pressure and heat to which the composition is subjected in this press is to compact the composition into a homogeneous mass, and to dry out the moisture 80 from the composition. This is generally 85 known as the "biscuiting" operation. After the biscuiting operation has been completed, the mold is withdrawn from the press, and the tooth is withdrawn from the mold. In taking the tooth away from the mold, the 90 pegs 12 retain their connection with the mold member 11, thus leaving holes 16 in the tooth, at the bottoms of which holes the conical anchor members 15 are embedded in the composition. 95

After being removed from the mold, the tooth is heated to a high degree of temperature, to effect the fusing operation. After this fusing operation has been completed, the tooth will be in condition shown in Fig. 100 3, with the conical anchor member 15 firmly embedded at the bottom of each hole 16. A small quantity of solder is then dropped into each of the holes 16, so as to fall into the interior of the cap 15. Securing pins 105 17 are then placed in the holes 16. These securing pins have conical ends 18, corresponding in shape with the internal shape of the conical anchors 15. With the pins 17 in place, the tooth is now subjected to a tem- 110

perature sufficient to melt the solder; and, when this temperature is reached, the pins are forced down so that their ends 18 engage firmly with the interior of the conical anchor 15. In this way, a secure soldered joint is made between the pins 17 and the anchors 15; and the pins 17 are thus rigidly connected with the body of the tooth.

In methods which have heretofore been proposed for molding an anchor into the body of the tooth, a great deal of difficulty has been met with in holding the anchor, during the molding operation, in an immovable position with respect to the peg, or the like, which was intended to support it. This difficulty has been wholly overcome by the device described above, since the engagement of the conical anchor 15 with the correspondingly-shaped conical end 14 of the peg 12 effectively prevents any relative movement between the anchor and the peg during the molding operation. Another difficulty has arisen, in connection with anchor devices of this general type, due to the small surface presented by the anchor for soldering to the end of the securing pin. This difficulty, likewise, has been overcome by the device described above, since the conical end 18 of the securing pin coöperating with the conical interior surface of the anchor 15 produces a considerably enlarged solder-receiving surface, to which the solder can readily flow upon the soldering operation being performed. The device provides an extremely effective means for rigidly fixing the securing pins to the tooth; and its use facilitates manufacture considerably and

minimizes the necessity of particular skill on the part of the operator.

Having thus fully described my invention, what I claim as new, and desire to secure by Letters Patent is:

1. An artificial tooth comprising a body member having a hole therein, and a hollow conical anchor member embedded in said body member and contained in said hole, the concave side of said anchor member being directed toward the opening of said hole.

2. An artificial tooth comprising a body member having a cavity therein, an anchor member embedded in said body member and contained in said cavity, said anchor member having a concave portion directed toward the opening of said cavity, and a securing pin disposed in said cavity and having an end of corresponding shape to the concave portion of said anchor member, the end of said pin being soldered to the concave portion of said anchor member.

3. The combination with a mold member having a cavity suitably shaped for forming the back of an artificial tooth, and a peg projecting into said cavity and having a conical end, with a bottom conical anchor member adapted to be placed upon the end of said peg, and thereby be maintained in position during the molding operation.

In testimony whereof, I the said WESLEY LINFORD SMITH have hereunto set my hand.

WESLEY LINFORD SMITH.
